UNITED STATES PATENT OFFICE.

WILLIAM MULLER, OF PITTSBURG, PENNSYLVANIA.

WRENCH.

No. 895,882.

Specification of Letters Patent. Patented Aug. 11, 1908.

Application filed January 31, 1908. Serial No. 413,545.

To all whom it may concern:

Be it known that I, WILLIAM MULLER, a citizen of the United States of America, residing at Pittsburg, in the county of Allegheny and State of Pennsylvania, have invented certain new and useful Improvements in Wrenches, of which the following is a specification, reference being had therein to the accompanying drawing.

10 This invention relates to wrenches, and the objects of my invention are, first, to provide a strong and durable nut and pipe wrench; and second to provide a wrench wherein positive and reliable means are embodied in a movable jaw for holding said jaw in a fixed position with relation to said wrench. I attain these objects by employing a double toothed shank upon which a jaw is slidably mounted. The jaw is provided 15 with two toothed gripping members, which are actuated through the medium of screws, these screws firmly holding the gripping members in engagement with the shank, and preventing the jaw from moving when the 20 wrench is being used upon an object. The movable jaw is also provided with a tilting pipe gripping jaw face.

25 The detail construction entering into my invention will be presently described and 30 then specifically pointed out in the appended claims.

35 In the drawings: Figure 1 is an elevation of a wrench constructed in accordance with my invention, Fig. 2 is a similar view of a portion of a wrench illustrating the movable jaw thereof in section, Fig. 3 is a horizontal sectional view taken on the line $x-x$ of Fig. 2, looking in the direction of the arrow of said figure, and Fig. 4 is a perspective view of the 40 tilting pipe gripping jaw face.

45 In the accompanying drawings, 1 designates a shank having teeth 2 upon its front and rear edges. This shank is provided with a fixed jaw 3 having a straight gripping surface 4 and an angular gripping surface 5, the former being for flat surfaces, while the latter is used for pipes and objects having rounded surfaces. The shank 1 is provided with a detachable handle 6 of a conventional 50 form.

55 Slidably mounted upon the shank 1 is a movable jaw frame 7 having a flat gripping

surface 8 adapted to coöperate with the flat gripping surface 4. Pivotaly mounted in the opposite edge of the jaw frame 7 by a pin 9 is a bifurcated pipe gripping jaw face 10, said jaw face having teeth 11 for gripping rounded surfaces. These teeth project beyond the plane of the face 8 and coact with the gripping face 5 of the jaw 3. The object 60 of the bifurcation in connection with this jaw will be presently described.

65 The jaw frame 7 is provided with a central opening 12 for the shank 1, and the upper and lower edges of said jaw frame adjacent to said opening are recessed, as at 13. Movably mounted in the opening 12 and engaging the front and rear edges of the shank 1 are gripping members 14, said members being provided with teeth 15 for engaging the 70 teeth 2 of the shank 1. The upper and lower ends of the members are formed with right angular extensions 16 adapted to engage in the recesses 13, while one of said extensions protrudes into the bifurcation of the 75 tilting gripping jaw face 10.

80 Adjustably mounted in the front and rear edges of the jaw frame 7 are screws 17 for engaging the members 14 and holding said members in engagement with the shank 1. To adjust the movable jaw, the screws 17 are slackened so that the operator, holding the jaw frame 7 in one hand, may, by forcing the shank 1 in either direction with the other hand, increase or decrease the space between 85 the gripping faces 4 and 8 and 5 and 11, and when the desired adjustment has been obtained, screws 17 will tighten and the jaw frame 7 will be held in adjusted position.

90 The construction of my wrench permits of an object being gripped and firmly held, it being impossible for the jaw frame 7 to slip after the members 14 have been placed in engagement with the double toothed shank 1.

95 It is apparent that my wrench serves functionally as an ordinary monkey wrench and a pipe wrench.

Having now described my invention what I claim as new, is:—

100 In a wrench, a shank carrying a fixed jaw and provided on opposite sides with teeth, a movable jaw having a central opening to receive the shank and having recesses at each end thereof, toothed gripping members

mounted in the central opening in said movable jaw to engage the opposite toothed surfaces of said shank, the said gripping-members being of the same length as the jaw and 5 provided at each end with angular extensions engaging in said recesses at the ends of the movable jaw, and securing screws in opposite faces of said movable jaw engaging

said gripping members for holding them in engagement with the teeth of the shank.

In testimony whereof I affix my signature in the presence of two witnesses.

WILLIAM MULLER.
